DEVICE FOR ADMINISTERING
ANESTHETICS

Ella S. Graybeal, Great Falls, Mont.

Application April 16, 1945, Serial No. 588,618

5 Claims. (Cl. 311—10)

1

This invention relates to a support for anesthetic administering devices.

An object of this invention is to provide an improved support for use on or adjacent operating tables for supporting injection elements in a convenient position and location so that the injection of one or more liquids may be accomplished quickly and with a minimum inconvenience or disturbance to the patient.

Another object of this invention is to provide a device of this kind which is freely adjustable so that the injection elements may be positioned at the desired point to effect the injection.

A further object of this invention is to provide a support of this kind which is of simple construction so that it can be built sturdily and at low cost.

To the foregoing objects and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a top plan view of the apparatus, Figure 2 is a side elevation.

Figure 3 is a sectional view, taken on line 3—3 of Figure 2.

Figure 4 is a sectional view taken on line 4—4 of Figure 3.

Figure 5 is a detail of one end of the arm rest board.

Figure 6 is a bottom plan view of the same end as Figure 5.

Figure 7 is a sectional view taken on line 7—7 of Figure 1.

Figure 8 is a sectional view taken on line 8—8 of Figure 7, and

Figure 9 is an end elevation taken on line 9—9 of Figure 3.

Referring now to the drawings the numeral 10 indicates the arm rest board having the spaced upper and lower members 11 and 12 respectively. The board 10 may be fastened to an operating table and extend outward or at right angles thereto.

Extending through the opening 13, and arranged slidably therein is a member 14 which may move to and fro and back and forth in the opening 13 and arranged on the member 14 is a slide 15 which completely encircles the member 14 and has positioned on its top side 16 a support or

2

standard 17, said standard having bifurcations 18 and 19 at its upper end for the reception therebetween of the projecting member 20 which is arranged with a supporting top 21 for retention thereon of a platform-like member 22.

The bifurcations 18 and 19 and the member 20 have holes therethrough for the reception of a bolt 23 and, preferably, a wing nut on the end of said bolt to hold said platform in adjustable stationary position.

Positioned on said platform 22 are the resilient members 28, 29, 30 and 31 which are of the flat spring type, quite resilient, and arranged for the reception and retention of any number of the syringes 32 and 33.

The syringe 32 has at its discharge end a three-way valve 34 to which both of the syringes are connected. This valve permits the contents of either or both of the syringes to be released into the hose 35 for injection through the needle 36.

The reservoir 37 is preferably made of a transparent substance so that if there is air in the line it may be eliminated before the injection takes place. The transparent reservoir 37 has the additional advantage of indicating when the needle has penetrated a vein, instead of a muscle, because the back-flow of blood from the vein will appear in the reservoir.

On the slide 15, at the foot of the standard 17, referring especially to Figures 7 and 8, there is provided a means to releasably retain said slide against the member 14, said means consisting, preferably, of a thumb screw 38 having a disc 39 at the forward end of its shank 40 and a threaded insert to receive the threads of said shank. It is apparent that pressure on the disc 39 will hold the slide against lateral movement with reference to the member 14.

Adjacent the board 10 and arranged for projection of the member 14 therethrough is a brace 45, Figures 3 and 9, which will prevent swaying motion of the member 14. The brace has an overlapping portion 46 which slidably rests on top of the upper arm rest member 11 while its vertical portion 47 is channeled to threadably receive the shank 48 of the thumb screw 49, the disc 50 of which will act against the member 14 when pressure is applied.

From the vertical portion extends a lateral projection 51 which has positioned at its outward end another thumb screw 52 and when screwed upward the disc 53 will impinge against the underside of the lower member 12. The double action of the two thumb screws will effectively prevent swaying of the member 14.

At one end of the member 14 I have provided a rotatable lock or catch 54 which is releasably held by the screw 55, and when released, may be turned to a vertical position, as shown in Figure 1, thereby preventing the member 14 from sliding away from the arm rest 11 when there is occasion to tilt the operating table.

Figures 5 and 6 illustrate, in detail, the construction of one end of the arm rest board, the upper and lower members 11 and 12, respectively, thereof having the spacer 60 between them. The opposite end also has a similar spacer between them.

The end legs 61 and 62 are fastened to the upper member 11 and the spacer 60 in any suitable manner, the legs being re-inforced by an angle and reinforcing plate 63, which also is attached to and supports the lower member 12, as clearly shown in the two above mentioned figures.

I have used the word board in a broad sense, wood, metal, plastic or any other suitable material may be used for making the various parts.

While this invention may be used in administering various types of anaesthesia it is particularly adaptable for giving an intravenous sodium pentothal anaesthetic, and it has the added advantage of easily being removable from one side to the other of the arm board or the operating table. The arm board is generally fitted to the surgery table by means of the legs 61 and 62 which fit into slides that are a part of the standard table.

The operation of the invention is made easy by its simplicity and is so constructed that one anaesthetist can perform the duties which usually require two such experts.

First, the arm board 10 is fastened to the surgery table, the member 14 positioned in the opening of said arm board may be longitudinally slid to the desired position. It may also be moved laterally of said arm board as may be the slide 15, thus furnishing a dual movement in this direction. The platform 22 may be tilted to any desired angle, all of these movements cooperating to allow the needle 36 to be manipulated at any desired point. Through operation of the three-way valve 34, either or both of the syringes may be brought into play.

What I claim is:

1. An apparatus for giving an anaesthetic comprising, an arm board, upper and lower members of said arm board, spacing elements to maintain said members in spaced relation, a member slidably positioned between said upper and lower members, and a means on said slidable member to hold an anaesthetic container.

2. An apparatus for giving an anaesthetic comprising an arm board including upper and lower members, spacing elements to maintain said members in spaced relation, a laterally extending member slidable longitudinally between said upper and lower members, means holding said latter member against all but sliding movement relative to said arm board, a second slideable member on said first slideable member, means locking said slideable members against relative movement therebetween, and an anaesthetic container supporting platform pivotally mounted on said second slideable member.

3. An apparatus for giving an anaesthetic comprising an arm board including upper and lower members, spacing elements to maintain said members in spaced relation, a laterally extending member slidable between said upper and lower members, bracing means slideable on said

upper and lower members and said slideable member for holding said slideable member against all but sliding movement on said arm board, locking means fixing said arm board, said slideable member, and said bracing means against sliding movement therebetween, a second slideable member on said first slideable member and an anaesthetic container supporting platform rockably mounted on said second slideable member.

4. An apparatus for giving an anaesthetic comprising a slotted arm board, a member slidably positioned in said arm board, a sliding clamp engaging said member and said arm board for fixing said member and said arm board together, a second slideable member on said first slideable member, and a means on said second slideable member to hold an anaesthetic container.

5. An apparatus for giving an anaesthetic comprising a slotted arm board, a member slidably positioned in said arm board, a clamp slideable on said arm board and said member, a second slideable member on said first slideable member, a platform rockably mounted on said second slideable member, and resilient clamping means on said platform for securing anaesthetic containers thereto.

ELLA S. GRAYBEAL.
